WORKMAN'S TIME RECORDER

Filed Jan. 26, 1927

UNITED STATES PATENT OFFICE

RICHARD D. SAWTELL, OF ATLANTA, GEORGIA, ASSIGNOR TO JAMES W. ANDERSON, OF NEW YORK, N. Y.

WORKMAN'S TIME RECORDER

Application filed January 26, 1927. Serial No. 163,676.

This invention relates to improvements in recording instruments and, more especially with reference to some of its details, it relates to improvements in workmen's time recorders or time clocks such as are utilized to make time records upon time cards or similar time sheets.

It is a general object of the invention to provide improvements in recording mechanism of the class mentioned, whereby operation thereof to make a record or impression on a workman's time card or a time sheet, or the like, is prevented at certain predetermined periods while such recording operation is permitted at other times.

It is a further object of the invention to provide in instruments of the class mentioned, an improved automatically controlled mechanism operating to prevent, at certain predetermined intervals, the making of an impression or record by the instrument, while permitting the same to be made at other times.

Still another object is to provide, in instruments of the class mentioned, a simple and efficient time controlled mechanism for obstructing, at certain intervals, a recording action of the instrument, thus preventing the workman from making a record on his time card or the like, as for example, during the lapse of a certain period of the work day, or after a certain time thereof.

Other objects will be pointed out in connection with the following detailed description of certain illustrative but preferred embodiments of the invention, and still others will be obvious in connection with such description.

The invention accordingly comprises the features of construction, combinations of elements, and arrangement of parts, which will be exemplified in the construction hereinafter set forth and the scope of the application of which will be indicated in the claims.

For a more complete understanding of the nature and objects of the invention, reference is had to the following detailed disclosure of the illustrative embodiments of the invention, and to the accompanying drawings in which,

Fig. 1 is a fragmentary, partially diagrammatic side elevation of a recording mechanism embodying the invention.

Fig. 2 is a view similar to Fig. 1, but showing a front elevation of the mechanism.

Fig. 3 is a fragmentary perspective view of a detail, showing the mechanism in a different position.

Fig. 4 is a view similar to Fig. 3, but showing a slightly modified arrangement, and

Fig. 5 is a central vertical section through a modified form of register obstructing plate.

Referring to the drawing for a detailed description of the different embodiments of the invention there shown, a frame work for supporting the various operative elements of the mechanism is shown generally at 10, Figs. 1 and 2. One or more type wheels or similar recording elements 11 are supported for rotation by means of a rotary shaft 12 mounted in the frame work. These type wheels are rotated by means of time controlled mechanism to bring the type characters upon the periphery thereof into registering position with a record sheet. The type upon these type wheels may be of any desired character,—for example, for indicating the day of the week and the time of day in hours and minutes.

The shaft 12 may be rotated by a time controlled operating mechanism including a toothed wheel 13 non-rotatably secured on shaft 12, and a driving pawl and ratchet mechanism 14 carried by a reciprocating member 15 pivoted on the frame 10. The member 15 is oscillated by means of a link 16, which is operatively connected to a time controlled driving member (not shown), such for example, as an electromagnet having a reciprocating armature and being intermittently energized by timed electric impulses controlled by time mechanism in a manner well known in the art.

Mounted adjacent to the type wheel in any suitable manner on the frame is a guide and support 17 having a slot or passage-way for the reception of a workman's time card or similar record sheet A. This time card is positioned by the support 17 to cooperate with the type characters of the

type wheel 11 so as to receive a printed impression thereby. Also an ink ribbon 18 is supported in any preferred manner to lie between the record or time card A and the periphery of the type wheels so as to supply 5 the ink for the printed impression.

The impression or imprint is effected on the card by means of a swinging hammer 19, which may have a resilient impact face 20 of 10 rubber or the like. The card guide and support 17 is so arranged as to interpose the time card between the hammer and the type. The hammer 19 is mounted for swinging movement by means of a rotary shaft 21 carrying 15 said hammer, and being rotatably mounted in the frame 10. The hammer arm is preferably pivotally mounted as at 22 on a short arm 23 fixed to the shaft 21, being restrained into slightly retracted position by means of a 20 spring 24 tensioned between the hammer arm and the arm 23. An arm 25 fixed on the shaft 21 carries a lug 26 cooperating with the lug 26' on the frame 10 to limit movement of shaft 21 and crank arm 23 during a forward 25 stroke of the hammer. A spring 27 is connected to an extension 25' on the arm 25 and to the frame 10, being tensioned to move the shaft in the direction of an operative stroke or blow of the hammer.

30 A manual operating mechanism for retracting the hammer 19 preparatory to an operative blow or stroke thereof, includes a handle 28 mounted upon the shaft 21 but being rotatable thereon and carrying a lug or 35 arm 29, to which is pivoted a pawl or dog 30 positioned for interlocking engagement with a tooth 31 on the arm 25 and having a tripping extension or tail 32 engageable with a tripping lug 33 mounted on the frame 10 by means 40 of a pin 34. Pivoted also to the outer end of the arm 29 is a connecting link 35 pivoted at its opposite end to a crank arm 36 non-rotatably secured to a shaft 37 rotatable in the frame 10. The shaft 37 is biased for rotation 45 in one direction by a spring 38, tensioned between its connection to the frame and the crank arm 39 fixed upon the shaft 37. This connection tends to move the operating handle 28 into set position with the dog 30 interlocked with the lug or tooth 31, as shown in 50 Fig. 1. The operation of this mechanism to retract the hammer 19 preparatory to delivering a blow against a time card to press it into recording contact with the type wheels, will be understood by those skilled in the art without further detailed description. The blow 55 of the hammer upon the part of the card A opposite to the type characters, will press or force this part of the card against the ink 60 ribbon and type characters so as to make a printed impression.

It is often desirable under certain circumstances that the instrument be rendered incapable of effecting a recording cooperation between 65 the time card and the type wheels.

For example, such a circumstance may be when the time, during which a workman may report for duty, has elapsed, when it is desired to prevent entry of a time record upon his card through operation of the recording instrument. One form of mechanism for accomplishment of this purpose is disclosed herein. 70

As shown in the drawing, a shield or obstructing plate 40 is carried by a supporting frame, or plate 41, which is mounted for movement transversely of the striking face of the hammer, and across the path of its operative movement. This shield is provided with an opening or cut-away, or discontinuous portion, 42, which may be moved into alignment with the path of the hammer or aligned therewith. When the aperture is aligned in the path of the hammer stroke, as shown in Figs. 1 and 2, a blow of the latter is delivered through said aperture against the time card to force or press the latter into cooperative recording position with the type wheels. When, however, the shield is moved to bring the aperture out of alignment with the path of the hammer, and to bring a part of the shield wall itself into alignment with said path, as shown in Fig. 3, a blow of the hammer will be delivered directly against the face of the shield, and the blow will be absorbed by said shield, thus preventing a registering cooperation between the time card and the recording element. Obstruction of the operative action of the hammer as described prevents delivery of a blow upon the time card which, therefore, will not be pressed into contact with the type wheels. 85 90 95

The obstructing plate or shield 40 is movable to or from obstructing position by means of supporting or guiding rods 43 connected to lugs 41' upon the shield support 41. These rods 43 are connected to support the plate 41 and are mounted for vertical sliding movement in guiding apertures in the frame 10. When the support 41 is elevated, as shown in Fig. 3, the blow of the hammer is directed against the face of the shield, and when lowered, as in Figs. 1 and 2, the face of the hammer is aligned with the opening 42. 100 105 110 115

The time controlled mechanism for controlling operation of the register obstructing mechanism will now be described. A timing wheel 44 is rotatably mounted on frame 10 being driven from the time controlled shaft 12 by a train of driving connections including a toothed gear 45 on shaft 12 meshing with a gear 46 on a shaft 47, carrying also a gear 48, meshing with a gear 49 on a shaft 50, which carries also a pinion 51 meshing with the timing wheel 44. The timing wheel carries operating cams or lugs 52, which may be mounted for angular adjusting movement with reference to the axis of the timing wheel, to vary the period of action of the 120 125 130 135 140

time control. A lever 53 is pivoted at one end to the frame 10 and has a cam or lug 54 co-operative with the lugs 52 to raise the lever 53 at predetermined intervals dependent upon 5 the positioning of the lugs 52. The lever 53 falls by gravity to the position shown in Fig. 2 as soon as the lug 52 passes from engagement with lug 54, rotation of the timing wheel being in the direction indicated by the arrow.

10 A link 55 connects the outer or swinging end of lever 53 with an arm 56 pivoted to the frame 10 and having a weight 57 at the free end thereof. A gravity shifter or automatic shifting pawl 58 is loosely pivoted to the 15 lever 56, and depends freely from its pivotal connection between two pins or lugs 59 on a pivoted arm 60 pivoted at its lower extremity to frame 10 and positioned between the lever 56 and the shifting pawl 58. The 20 pawl 58 is shaped at opposite lateral sides thereof to provide similar lugs 61 for alternate cooperation with the respective adjacent lugs 59. The crank arm 36 is provided with an inward extension 36', at the inner end of 25 which is pivoted a link or pitman 62, extending upwardly and provided near its upper extremity with a seat 63 and a wide guiding slot 64. This slot spans a shaft 65 for retaining the pitman in an upright operative 30 position, but permits a limited lateral swinging movement of the upper end of the pitman.

The lever 60 has an extension 60' lying adjacent the pitman 62 and carrying a pin 66 slideable in a slot 67 in the pitman, where- 35 by lateral swinging movement of the lever 60 effects a corresponding lateral movement of the pitman. As the pitman 62 swings to the left in Fig. 1 the seat 63 thereof moves into alignment under a pin or lug 68 on the inner 40 side of an arm 69 secured on the rotary shaft 65 to swing in a vertical plane. Upward longitudinal movement of the pitman will, therefore, cause the arm 69, and a similar spaced arm 69 mounted on shaft 65, to swing 45 upwardly. The arms 69 being connected to the support 41 as at 69', it will be seen that upward movement of these arms will effect an upward movement of the obstructing plate or shield 40 into register obstructing position 50 relative to the hammer 19, as shown in Fig. 3.

This upward movement of the pitman 62 is effected at each depression of the operating handle 28, and a registering cooperation will therefore be prevented so long as the pitman 55 remains in its left position, Fig. 1, by virtue of the automatic positioning of the shield 40 in obstructing position at each depression of the handle. However, when the pitman is 60 swung to the right, the seat 63 is disaligned with lug 68 and depression of the handle 28 does not disturb the operative position of the shield, as shown in Fig. 1.

It will be understood that the positioning of the pitman 62 in operative or inoperative position is effected by the timing wheel 44,

through the connections described. When the automatic pawl member 58 is raised by operation of the timing wheel, it swings by gravity from the position shown in Fig. 1, as soon as free from engagement with the left pin 59, 70 into position for engagement with the right pin 59. The descent of the gravity member 57 carries the pawl downwardly into engagement with the right pin 59 in such a manner as to swing the lever 60 to the right in Fig. 1, 75 thus shifting the pitman 62 into inoperative position. The pins 59 at the same time are reset relatively to the pawl, so that the latter is reengaged with the left pin 59 at the next rising and falling movement of said pawl, 80 which is effected by operation of the next successive cam 52 on the timing wheel.

It will be observed that obstruction to the registering cooperation between the time card and the type wheel could also be effected by 85 locking the hammer operating mechanism against operative action by means of a locking device controlled by movement of the lever 60, or similarly by interposing an obstruction in the card guide and support 17 to prevent insertion of a time card at predetermined times. This locking mechanism or card obstructing mechanism would be controlled by the time wheel in a manner similar to the control thereby of the hammer obstructing plate.

A semaphore or signal member 70 may be utilized for notifying a workman that the machine is set in inoperative position. Such a signal may, as shown, be carried on a vertically disposed rotatable rod 71 having a crank 72 connected to the extension 60' of lever 60, as indicated at 73, whereby the semaphore is rotated through about 90° during each swinging movement of the lever 60. The semaphore 70 may bear certain indicia to notify the workman of the condition of the registering instrument, such indicia being presented or withdrawn from a window or opening in the casing instrument by operation 105 of the time controlled mechanism.

A preferred embodiment of the invention is shown in Fig. 4 in which the arrangement generally is the same as the above set forth, and corresponding parts are designated by the same numerals with the addition of the index "a". The arrangement of the type wheels is the same as before, but the obstructing shield 40a is of the form shown, and supported by a support 41a mounted for up and down movement by means of the guiding rods 43a. The swinging arms 69a are connected to the support 41a through links 74 for raising the obstructing plate 40a into obstructing position, or lowering it into non-obstructing position, in which latter position it is shown in Fig. 4: in this position the hammer 19a may press a time card or the like into contact with the type wheel 11 through the intermediate ink ribbon 18a which may be supported in 110 115 120 125 130

any preferred manner. When the obstructing plate 40^a is raised it lies in the path of the hammer and is encountered thereby to obstruct its operative action as described above.

- 5 The inner side of the obstructing shield 40^a may be faced with a resilient pad 75 of rubber or other resilient material, or the shield itself may be made of such material. Also, as shown in Fig. 5, the inner side of the shield 40
10 opposite the type wheels may be faced with resilient material 75. This construction provides a cushion to protect the type from damaging blows by operation of the hammer. This may be desirable, for example, in case
15 the type of the type wheels is made of soft material, as rubber.

A two-color ribbon may be utilized and shifted in the ordinary manner to give one color record during a certain period of time
20 and another color during a different period of time. For shifting the two-color ribbon at timed intervals and holding the particular color in printing relation to the type for the periods of time desired, it may be carried by
25 a vertically reciprocal shifting frame, time controlled in the manner hereinbefore explained for the obstructing shield 40. The obstructing shield 40 with its time controlling devices would thus be time controlled supplemental to the two-color ribbon shift mechanism. With such an arrangement, registrations during one time period, morning, for instance, could be in one color, and registrations in the afternoon could be in another
30 color, and the shield 40, at predetermined intervals, controlled by its timing mechanism, could move either into or out of position to prevent registration by either color, each condition enduring for any predetermined
35 40 interval of time desired.

Since certain changes may be made in the above construction, and different embodiments of the invention could be made without departing from the scope thereof, it is intended that all matter contained in the above description or shown in the accompanying drawings shall be interpreted as illustrative and not in a limiting sense.

It is also to be understood that the following claims are intended to cover all of the generic and specific features of the invention herein described, and all statements of the scope of the invention which, as a matter of language, might be said to fall therebetween.

55 Having described my invention, what I claim as new and desire to secure by Letters Patent is:

1. In a device of the character described, in combination, recording mechanism for
60 making an impression or record on a record card, or the like, and a mechanism operating under joint time and manual control to prevent at predetermined timed intervals the making of a record by said recording mechanism.

2. In a device of the character described, in combination, recording element, time controlled mechanism to set said recording element for making different records, mechanism for effecting a recording cooperation between said recording element and a record sheet, or the like, and a shield movably mounted adjacent said recording element, and movable into and away from position to obstruct a recording cooperation between said recording element and the record sheet. 70

3. In a device of the character described, in combination, a recording element, time controlled mechanism to set said recording element for making different records, mechanism for effecting a recording cooperation between said recording element and a record sheet, or the like, a shield movably mounted adjacent said recording element, and movable into and away from position to obstruct a recording cooperation between said recording element and the record sheet, and time controlled mechanism to move said shield at predetermined intervals into position to obstruct recording cooperation between said recording element and the record sheet. 75

4. In a device of the character described, in combination, a recording element, time controlled mechanism to set said recording element for making different recording impressions, manually operable mechanism for effecting a recording cooperation between said recording element, and a record card, or the like, and time controlled mechanism operable at predetermined intervals for rendering said manually operable mechanism ineffective to cause a recording cooperation between said recording element and the record card while permitting operation of said manually operable mechanism. 80

5. In a device of the character described, in combination, a recording element, time controlled mechanism to set said recording element for making different recording impressions, manually operable mechanism for effecting a recording cooperation between said recording element and a record sheet, or the like, and a shield movably mounted adjacent said recording element and operable by said manual mechanism to obstruct, at predetermined intervals, a recording cooperation between said recording mechanism and record sheet. 85

In testimony whereof I affix my signature.

RICHARD D. SAWTELL. 100
